P. A. GEIER AND F. E. ROBERTSON,

HANDLE MEMBER,

APPLICATION FILED MAR. 25, 1916.

1,349,828.

Patented Aug. 17, 1920.

UNITED STATES PATENT OFFICE.

PHILIP A. GEIER AND FRANK E. ROBERTSON, OF CLEVELAND, OHIO, ASSIGNEES TO
THE P. A. GEIER COMPANY, OF CLEVELAND, OHIO, A CORPORATION OF OHIO.

HANDLE MEMBER.

1,349,828.

Specification of Letters Patent. Patented Aug. 17, 1920.

Application filed March 25, 1918. Serial No. 86,589.

To all whom it may concern:

Be it known that we, PHILIP A. GEIER and FRANK E. ROBERTSON, citizens of the United States of America, residing at Cleveland, in the county of Cuyahoga and State of Ohio, have invented certain new and useful Improvements in Handle Members, of which the following is a specification:

This invention relates to improvements in handles, and has for its object, the provision of a light rigid handle member, especially adapted for vacuum cleaning apparatus of the motor driven type.

Such handles are now commonly made from sheet metal tubing, in order to afford sufficient rigidity, and provide a conduit for electric wires, and a suitable receptacle for the controlling switch. Metal handles are conductors of electricity, thereby affording a possibility for grounding the electric circuits, and the weight thereof, is greater than is desirable or necessary. Accordingly, we have adopted a fiber tube, which may be made of the desired length. However, it has been found that such fiber tubing, of the requisite length, is very liable to warp, and render the handle unadapted for use. To remedy this, we have provided an interior core, preferably of wood, and of such shape as to bear upon the inner periphery of the tube, at a plurality of angularly disposed points for maintaining the tube in alignment, while affording at the same time, a suitable and unobstructed passage for the current conducting wires.

To accommodate the switch, we preferably slot the end of said tubing, and maintain the switch in position by means of its protruding buttons, which extend through the slots in the tube. A suitable bent terminal also is provided, which preferably is formed of fiber, and which contains a block to afford an anchorage for a mounting screw, adapted to unite the handle and the tubing handle members.

Further details of construction will be explained in connection with the accompanying sheet of drawings, wherein:

Figure 1 is a fragmentary view in longitudinal section of the upper portion of the handle member.

Fig. 2 is an intermediate fragmentary portion of the handle, illustrating the tubing and its wooden core.

Fig. 3 is a transverse sectional view on line 3—3, and

Fig. 4 is a plan view of the upper portion of the handle member.

Throughout the several figures of the drawings, we have employed the same character of reference to indicate similar parts.

The tube *a*, of fiber, which is shown in full size in our original drawings, is stayed throughout approximately its entire length, by a wooden core *b*. The core as best shown in Figs. 2 and 3, is provided with three ribs, which are adapted to fit snugly within the inner periphery of the tube, and prevent it from warping, as well as affording some slight additional rigidity. The insulated conducting wires *c*, are adapted to extend within the tube, and along said core; the same being connected to a switch *d*, positioned adjacent to the upper end of the tube, which is diametrically slotted at *a'*, (Fig. 4), from its end, to accommodate the protruding push buttons *d'* of the switch.

A stiff wire spring *e*, protects the extension *c'*, of the conducting cord, from abrupt bending at the points of its entrance within the tube. A wooden block *f*, occupies the terminally slotted section of the tube, while a bent tubular handle member *g*, also of fiber, is adapted to telescope over the slotted end of the tube, and be held in place by a transverse screw *h*, seated within the telescoping portions of the tubes, and the contained wooden block. As a finishing member, a semispherical wooden block *i*, may be inserted at the end of the handle member *g*.

As thus constituted, the handle described, is of extreme strength and lightness. Its rigidity is sufficient for all purposes, and it is practically unbreakable, under conditions of ordinary use. The inherent difficulty of fiber tubing, is obviated by reason of the wooden core, which adds little to the weight, while the switch is made readily removable and accessible, merely by removing the screw *h*, and the terminal handle member *g*. Accordingly, the con-

struction is well adapted for continued use, and is not as tiring to the operative, as is a heavier metal handle, nor is it liable to ground the conducting wires.

5 Moreover, a straight metal tube presents difficulties in the way of mounting the switch, which an insulating tube eliminates. The telescopic fiber tubing, and the terminal handle portion, permit of strengthening 10 the connection by inserting these members, as far as desired, one within the other. Contrasted with this, is the provision of a 15 wooden or other insulating handle portion, which ordinarily must be mounted upon a metal tube, to complete the handle member formed therefrom.

Having now described the preferred handle member of our invention, we claim as new, and desire to secure by Letters Patent, 20 the following:—

1. A composite handle member, comprising 25 a length of fiber tubing, a wooden core snugly engaging said tubing interiorly substantially throughout its length, a block fitted within the upper end of said tubing,

a terminal handle telescoping over said tubing and block, and means for uniting the tubing and handle, substantially as set forth.

2. A composite handle and a conduit, 30 comprising a length of fiber tubing, a wooden core fitting approximately the entire interior of said tubing, and grooved longitudinally; said tubing being terminally slotted, a switch fitting within the slotted portion of the tubing, electric conductors extending from said switch interiorly of the tubing, a block interiorly mounted beyond the switch, a tubular fiber handle portion telescoping over the tubing, and securing means extending through the handle portion, tubing and block, substantially as set forth. 35

In testimony whereof we do now affix our signatures in presence of two witnesses. 40

PHILIP A. GEIER.

FRANK E. ROBERTSON.
